UNITED STATES PATENT OFFICE

FRANK C. DE REAMER, OF BRIDGEPORT, CONNECTICUT, ASSIGNOR TO GENERAL ELECTRIC COMPANY, A CORPORATION OF NEW YORK

SNAP SWITCH

Application filed February 1, 1928. Serial No. 251,167.

The present invention relates to small snap switches and has for its object to improve their construction. The invention is particularly applicable to switches for use with manually-operated devices such as vacuum cleaners, electric drills, etc. and will be described in connection with such a device although it is not to be understood as being limited thereto.

For a consideration of what I believe to be novel and my invention, attention is directed to the accompanying description and the claims appended thereto.

In the drawing, Fig. 1 is a view of the switch in side elevation showing it mounted in the tubular handle of a vacuum cleaner; Fig. 2 is a perspective view of the switch; Fig. 3 is an exploded perspective view of the frame and some of the parts; Figs. 4 and 5 are side views of the switch on an enlarged scale showing the movable contact in different positions; Fig. 6 is an end view of the switch partly in section and partly in elevation, Figs. 7 and 8 are perspective views on an enlarged scale of the actuator or trigger and illustrating how it is made and Fig. 9 is a detail view showing the mounting of the binding screws.

In making small switches the chief problems among many others are to provide a structure in which the parts are simple, cheap to construct, light and strong, and which are capable of operating for a long period of time without injury either to the electrical or mechanical elements. Also, to provide a structure the parts of which can be made in large quantities and assembled by the ordinary class of help available for the purpose.

Having briefly outlined the principal features which a small switch should have, I will now describe the means by which they are attained.

The frame comprises a head member 10 which in this case is round but not necessarily so, and a second member 11 extending at right angles thereto and standing edgewise said parts being riveted to each other by tongues 12 formed on the member 11 as indicated in Fig. 4. Two such tongues or rivets are provided which ensures a rigid relation of the

members. The two members are punched out of sheet steel and at the same time the various holes and notches are or may be formed. The head member is secured to a handle 13 or other support by two screws 14 located on opposite sides of the second or longitudinal member 11.

The second member is best illustrated in Fig. 3 wherein 15 indicates an upwardly-extending V-shaped notch in the side walls of which act as stops for the movable contact-carrying arm or element 16. The element 16 is in the form of an inverted U with the legs thereof straddling the frame member 11. Extending through said legs is a bar 17 which performs a double function,—that is to say, the central part of the bar between the legs strikes first on one wall and then on the other of the V-notch as the contact moves to open and close the circuit while the ends project beyond the legs and receive the upper ends of the coiled extension springs 18. Two such springs are provided so as to equalize the strain on the associated parts. The bar makes a loose fit in the two legs of the contact-carrying element or arm 16 and the two springs engaging the opposite ends thereof serve to hold it central.

By using two relatively light springs and locating them on opposite sides of the contact-carrying element 16 and frame member 11, the assembly operation is simplified because they are easier to mount than one relatively stiff spring, especially if it has to be mounted between other parts as is the common practice. Below the V-notch with the walls thereof diverging in the opposite direction is a V-shaped or triangular opening 19. The lower bar or wall 20 of the opening forms a guiding or cam surface on its upper side and on which the trigger or actuator 21 travels the latter being guided in its to-and-fro movements by said wall as well as by the slide surfaces of the frame member 11 as shown in Fig. 6. The portion of the wall located at the apex of the opening forms the fulcrum for the actuator or trigger, as best shown in Fig. 8. The construction of the actuator or trigger is best shown in Figs. 7 and 8. It is made of thin sheet steel and is blanked out by a die from

the sheet in the form shown in Fig. 7. It comprises a handle 22, a pair of legs 23 which straddle the frame, each of which has an out-turned lug 24, said lugs forming pivots for the contact-carrying element 16 and being located on opposite sides of the frame member 11. The actuator is also provided with a second pair of out-turned or laterally extending lugs 25, and seated in the notches thereon are the lower ends of the actuating springs 18. The inner or bottom end of the slot between the legs is enlarged to form a square or rectangular slot 30, the walls of which engage and ride on the wall or cam bar 20 of the frame member 11. The actuator or trigger is assembled in place on the frame by squeezing or forcing the two legs thereof into contact as best shown in Fig. 8, so that one part is within the opening and 10 engaging the fulcrum and the other part overlies the frame member and is guided thereby. From the foregoing it will be seen that the contact-carrying member 16 is carried solely by the two pivots 24 which also 20 actuate it in a manner to be described later.

As above stated, the trigger while it is not pinned to the frame nevertheless is held within the slot 19 by reason of having its two legs squeezed together, an arrangement which is 30 simple yet effective for the purpose. The trigger 21 and the contact-carrying element 16 form a toggle and the springs act to snap the moving contact to both its closed and open positions. It will be seen from Fig. 6 35 that the shoulder 30^a on the trigger engages that portion 11^a of the frame member which lies between the bottom of the V-shaped notch and the apex of the opening 19, and that said portion serves as a fulcrum for the 40 trigger. The movements of the trigger are limited by the shoulders 11^b which are situated below the cam bar or guide 20.

On opposite sides of the frame member 11 are mounted two pieces of insulation 31 45 which are substantially rectangular in outline, having one corner cut away to prevent interference with the contact carrier, or pole piece, and a notch 32 on the underside to receive the nut 33 by means of which the switch 50 frame is secured to the tubular part 34 of the handle of the vacuum cleaner or other device to be controlled by the switch. The notches in the insulating sheets as well as the notch 35 in the frame are of T-formation. The 55 central part of the nut occupies the larger part of the slot and the sides of the nut are bent over, all of which prevents the nut from turning or being pulled out and also acts as means to hold the insulation in place. The 60 insulation is further clamped to the frame by a pair of hollow rivets 36 of usual construction.

On each side of the frame and insulated 65 therefrom is a stationary contact member 37 and a binding screw 38 for a current-carry-

ing conductor. The nut for each screw is supported by a bridge piece 39 to keep the screw and conductor away from the frame, and the ends of the bridge piece, Fig. 9, extend through the base of a contact member 70 and the insulation and the ends of the bridge piece are turned over to fasten them in place. The frame is cut away opposite the turned over ends of the bridge to prevent short-circuiting. This arrangement permits of assembling the parts on the insulation and later fastening the same to the frame member 11.

In any switch, and especially after continued use, there is a tendency for the contact surfaces both moving and stationary to become rough due to arcing. This in time 80 may render the switch useless. To guard against or prevent roughening of the surfaces, the movable or bridging contact 40 which is carried by and insulated from the element 16 is given a positive rubbing or wiping movement each time it is opened and the circuit interrupted. This is accomplished by mounting the pivots 24 for the carrying element 16 on the actuator or trigger instead of mounting them on the frame. As a result of the construction described, when the actuator 21 starts to move from the full line to the dotted-line position of 95 Fig. 4, the contact-carrying element is first given a limited movement in the direction of its length and at the same time a slight turning or twisting motion, the two said movements causing the moving and stationary contacts to rub one on the other and thus 100 keep the surfaces bright, clean and smooth. This is due to the fact that trigger 21 and contact-carrying element 16 form two arms of a toggle with the springs tending to collapse them. Since the trigger cannot move downwardly on account of the cam bar 20 on which it rides and since in straightening a 105 toggle it lengthens, it follows that all of the longitudinal movement is concentrated in the contact-carrying element thereby giving the moving contact a wiping or rubbing engagement with the pair of stationary contacts. This movement continues until a plane passing through the end supports for each spring 110 crosses over the pivots 24 when the springs act to complete the movement of the contact carrying element with a snap action, thereby 115 quickly and certainly interrupting the circuit.

The switch is thin due to the location and arrangement of the frame member 11 and as a result ample space is afforded for the conductors which are attached to the binding screws on each side thereof. To guard 120 against short-circuiting due to poor wiring, it is desirable to encase the switch in an insulating tube or container such as 42 which is located within the tubular part of the handle.

One of the features which distinguishes my improved switch over the prior art resides in the fact that while the actuator or trigger is held within the opening 19 due to its peculiar formation there are no pivots carried by the frame for supporting it. Another distinguishing feature is that the arm or element 16 which carries the movable contact instead of being pivoted to the frame is 10 pivoted to the trigger or actuator.

Still another distinguishing feature is the positive wiping or rubbing action of the movable contact on the stationary contacts prior to each opening movement thereof. This is due 15 to the fact that the contact-carrying arm or element is pivoted directly on the trigger or actuator and hence is positively moved in a generally longitudinal direction by it until the members of the toggle and their pivots lie 20 in the same plane. During the straightening movements of the toggle the moving contact of course also turns or twists slightly with respect to the fixed contacts.

What I claim as new and desire to secure 25 by Letters Patent of the United States, is:

1. A snap switch comprising a frame having a relatively large opening, the wall of which defines a fulcrum, a relatively thin actuator having a part which fits into said 30 opening and rests on the fulcrum and another part which overlies the sides of the frame, said portions serving to hold the actuator in place, a contact and a supporting element therefor which are moved by the actuator, 35 and a stationary contact carried by the frame which is engaged by the movable contact.

2. A snap switch comprising a thin, flat frame member having a V-shaped fulcrum, a stationary contact supported by the member, 40 a movable contact adapted to establish a circuit through the stationary contact, an actuator through which the frame member extends and which has a swinging movement on said fulcrum, an element which is pivotally 45 connected to and supported by one end of the actuator so that when the actuator is moved it positively causes the contacts to rub one on the other, and spring means connecting the actuator and element which completes the 50 movements of both the element and actuator, which movements are started by the actuator.

3. In a snap switch, the combination of a frame member having a V-shaped notch, the walls of which define stops, stationary and 55 movable contacts, a pivotally-supported element which carries the movable contact, a pivotally-supported actuator for the element, a bar which freely extends through the element and forms a stop to engage one wall or 60 the other of said notch, and springs which connect the ends of the bar to the actuator.

4. In a snap switch, the combination of a frame having a V-shaped notch, stationary and movable contacts, a supporting element 65 for the movable contact which has a pair of

legs that straddle the frame, an actuator for the element mounted to swing on the fulcrum formed by said notch, a bar which freely extends through both legs of said element and alternately strikes on the walls of the notch, and a pair of springs, one on each side, which connect the ends of the bar to the actuator. 70

5. A snap switch comprising a frame member having an opening one wall of which forms a cam surface, a trigger mounted to move on the said surface, a stationary contact, a movable contact, a contact-carrying element, a pivot means carried by the trigger which forms the support for the element and which imparts to the movable contact a rubbing movement on the stationary contact prior to opening the circuit, and a spring which is connected to the trigger and element for actuating the moving contact when the trigger is moved from one of its positions 80 to the other. 85

6. A snap switch comprising a flat frame member, having an opening one wall of which forms a cam surface, a trigger having a pair of legs which fit into the opening 90 and which rides on the cam, a pair of pivots carried by one end of the trigger, a contact, a carrying element therefor, the legs of which are supported by the pivots, a pair of stationary contacts which are bridged by the 95 moving contact, and a pair of springs which connect the element to the trigger and which move the contact when in their movement they cross said pivots. 100

7. A snap switch comprising a flat member which stands edgewise and has a notch in one edge and an opening near the other, the lower wall of said opening forming a cam surface, a trigger which is partly located in said opening and has a portion which rides 105 on the surface of the cam, pivots carried by the trigger, a pair of stationary contacts, a bridging contact, a U-shaped element which carries the bridging contact and is itself solely supported by the pivots on the trigger, said trigger and element forming a toggle, the endwise movements of which are limited by said cam to the element, and a spring connected to the trigger and element which actuates the bridging contact as it moves across 110 the pivots of the element. 115

8. A snap switch comprising stationary contacts and a bridging contact, an element which carries the bridging contact, a trigger on which the element is pivoted, said element 120 and trigger forming a toggle, a fixed fulcrum for the trigger, an overset spring for actuating the element when the trigger is moved, a support for the parts, and a cam means which confines the endwise movement of said 125 toggle parts to the element when the trigger is moved from one of its positions to the other.

9. A snap switch comprising a thin metal frame member which stands edgewise and 130

has a V-shaped notch in one edge and an opening near the other edge, one wall of which opening forms a cam, a trigger which moves back and forth in the opening and is guided in its movement by the cam, a U-shaped element which straddles the frame and is pivotally connected to the trigger, stationary contacts carried by and insulated from the frame, a bridging contact carried by the element, and springs located on opposite sides of the frame member which cause the element and its contact to move with a snap action when the trigger is actuated.

10. In a snap switch, the combination of a frame member, a trigger which straddles the frame, a cam surface on the frame which holds the trigger against endwise movement and guides it in its to and fro movements, an element which straddles the frame and trigger, pivots independent of the frame which connect the adjacent ends of the trigger and element, a pair of stationary contacts carried by the frame member, a bridging contact carried by the element, and a pair of springs one on each side of the frame, which cause said element to move when the trigger is actuated.

11. In a snap switch, the combination of a frame member having stops, a trigger which straddles the frame, a cam surface on the frame which holds the trigger against endwise movement and guides its swinging movements, an element which straddles the frame and trigger, pivots which connect the adjacent ends of the trigger and element, a bar which extends through the element and is arranged to strike said stops to limit the movements of the element and which also serves as attaching means for the actuating springs, and a pair of springs one on each side of the element and trigger which connect them and serve to move said element when the trigger is actuated.

12. In a snap switch, the combination of a thin, flat frame member, stationary contacts carried thereby, a movable contact, an element on which the movable contact is supported and which straddles the member, a trigger which is pivotally supported on the frame member and through which trigger the frame member extends, said trigger having a pair of outwardly-extending pivots on which the said element is supported and a pair of outwardly extending lugs, and springs which are attached to said lugs at one end and to said element at the other.

13. A snap switch having a frame comprising a head on one end, and a single piece flat member extending perpendicular thereto, said parts being united, a contact-carrying element, a trigger, both of which straddle the frame member and form parts of a toggle, cam means for guiding the trigger in its movements, pivots for said element which are carried by the trigger, stationary con-

tacts carried by the frame member, a contact on said element, and springs which connect said element and trigger whereby movement of the trigger is imparted to the element and the contact carried thereby.

14. In a snap switch, the combination of a frame member having an opening one portion of which is shaped to form a fulcrum, an actuator, a portion of which is located within the opening and is held in place thereby, one part of said portion resting on the fulcrum, a pivoted contact-carrying element, spring means connecting the actuator and element, and a contact which is adapted to be engaged by the one on the element when the actuator is moved.

15. In a switch, the combination of a flat frame member, insulating material mounted on the sides thereof, said member and material having a T-shaped slot, a nut mounted in the slot and having bent-over edges which prevent the nut from turning, a casing, and a screw which passes through the casing into the nut for uniting the parts.

16. A snap switch comprising a thin, flat frame member, a fixed contact supported thereby, a movable contact, an element which carries the movable contact and straddles the frame member, an actuator pivoted on the frame member for moving the element and through which the frame member extends, said element straddling the actuator, a pivot for the element which is carried by the actuator and forms its sole support, said actuator and element forming a toggle, and a coil spring connected at one end to the element and at the other end to the actuator, which spring when it crosses the dead center moves the element with a snap action to open or close the circuit and which also completes the movements of the actuator.

In witness whereof, I have hereunto set my hand this thirtieth day of January, 1928.
